UNITED STATES PATENT OFFICE

116,848

DESIGN FOR A ROLLER SUPPORTING ARM FOR A LAWN MOWER

Marlowe H. Kluter, Richmond, Ind., assignor to
The F. & N. Lawn Mower Company, Richmond, Ind., a corporation of Delaware

Application April 5, 1939, Serial No. 84,070

Term of patent 14 years

To all whom it may concern:

Be it known that I, Marlowe H. Kluter, a citizen of the United States of America, residing at Richmond, in the county of Wayne and State of Indiana, have invented a new, original, and original Design for a Roller Supporting Arm for a Lawn Mower, of which the following is a specification, reference being had to the accompanying drawing, forming part thereof.

Figs. 1 and 2 are side elevations of the inside and outside faces, respectively, of a roller supporting arm for a lawn mower embodying the design.

I claim:

The ornamental design for a roller supporting arm for a lawn mower, as shown.

MARLOWE H. KLUTER.
